UNITED STATES PATENT OFFICE.

DARIO ROBERTI, OF SPRINGFIELD, MASSACHUSETTS.

COMBINATION LOCK.

Application filed April 12, 1927. Serial No. 183,066.

My invention relates to improvements in combination locks adapted for use on drawers, dress-suit cases, and the like, and particularly applicable for use in connection with the ignition switches of automobiles, and consists generally of a lock case attachable to and removable from a plate, and provided with a hinged cover, said case containing a spring-pressed, main lock bolt, retracting means for said bolt, means to hold said bolt in retracted position, spring pressed, permutation lock-bars for said bolt, mechanism to impart a step-by-step movement to said lock-bars, including releasing means therefor, an auxiliary, spring-pressed lock bolt mounted on said plate in position to be engaged by said main bolt, and adapted when disengaged therefrom to assist the same in locking said case to said plate, a spring of peculiar construction adapted, when normally disposed, to prevent said lock-bars from sliding out of channels provided in said cover to receive them, when said cover is open to retain said releasing means normally in engagement with said lock-bars, and to throw open said cover when unlatched, together with such other parts and members as may be necessary or desirable in order to render the lock complete and serviceable in every respect, all as hereinafter set forth. The lifters with their push-pins, and certain others of the parts and members of this lock are new and novel apart from the combination or combinations of which they constitute elements.

This invention is in the nature of an improvement of the combination lock covered by Letters Patent of the United States, No. 1,568,624.

One object of my invention is to produce a combination lock adapted for use in connection with the ignition switch for the engine of an automobile, whereby the movable members of said switch are locked in out-of contact position when the combination is distributed, and permitted to be moved, when said combination is set, into position to close the circuit through the coil and the magneto, and capable of being moved to close the circuit through said coil and battery when the latter forms a part of the ignition system of the machine. This lock is adapted to have the combination set by imparting to one or more of the lock-bars, through the medium of push-pins which correspond in number with said lock-bars, a predetermined number or numbers of pulsations. When the

combination is set both bolts are released and can be withdrawn from locking position and held out of such position. Thus it is seen that only a person having the correct combination can unlock the ignition-switch to enable it to be used to start the engine, or unlock the case from the plate, which plate is securely attached to the instrument-board of the automobile.

Another object is to provide a combination lock of this character that is adapted for use apart from ignition switches, and this without materially changing the construction of said lock.

A further object is to produce a combination lock which consists of comparatively few parts and those parts comparatively simple in construction and operation, while at the same time the lock is safe, secure, easy to operate, and withal entirely practical and highly efficient.

Still another object is to afford ready means for obtaining access to the interior of the case, for the purpose of changing the combination of the lock, without, by affording such means, detracting from or decreasing the safety and security of said lock. It is to this end that the provision is made for locking the case to and unlocking it from the plate.

Other objects and advantages will appear in the course of the following description.

I attain the objects and secure the advantages of my invention by the mechanism illustrated in the accompanying drawings, in which—

Figure 1 is a front elevation of a combination lock which embodies a practical form of my invention, the same including the ignition-switch locking feature; Fig. 2, a left-hand side elevation of said lock, with a portion of the fixed switch element in section; Fig. 3, a rear elevation of the lock with portions broken away to disclose parts that otherwise would be hidden; Fig. 4, a rear elevation of the lock, with the cover of the case open, and parts broken out and in section; Fig. 5, a vertical section through the lock, taken on lines 5—5, looking in the direction of the associated arrow in Fig. 4, the cover here being closed; Fig. 6, a rear elevation of the lock without the cover, and with parts broken away and in section; Fig. 7, a right-hand end elevation of the lock with the cover closed; Fig. 8, a bottom plan of the lock, the case being in section, as on lines

8—8 in Fig. 6; Fig. 9, a rear elevation of one of the lifters and its push-pin; Fig. 10, a side elevation of said lifter and push-pin; Fig. 11, a detail including a portion of the 5 main bolt of the lock when adapted for a suit-case, and Fig. 12, a similar detail showing said bolt in unlocked position.

Similar reference characters designate similar parts throughout the several views.

10 Although I have illustrated this combination lock in connection with an ignition switch, and will so describe the same, it is to be understood, as hereinbefore intimated, that the lock is susceptible of a variety of 15 different applications or uses, hence I do not desire or intend to restrict the same in these respects, except in so far as certain of the claims include the switch elements.

Preferably a plate, such as that represented 20 at 1, or its equivalent, is provided as a part of this combination lock. The plate is, in practice, securely attached to the instrument-board of an automobile, if said lock is to be used in connection with the ignition 25 switch of the machine, or to the front of a drawer or one side of a door, or to one side of a receptacle of the dress-suit case type. In the plate 1 is a rectangular opening 2 provided to receive a rectangular case 3. The 30 case 3 has a flange around the front side to overlap the edges of the opening 2. Two screws 4 are employed to fasten the flange at the top and bottom of the case 3 to the plate 1, said screws being passed through 35 said flange and tapped into said plate. Fastened to the back side of the plate 1, adjacent to one vertical edge of the opening 2, are two spring clips 6 having rearwardly extending lips provided with pins 7—7 that extend 40 over said opening. Recesses, represented at 7'—7' in Fig. 6, are made in the side of the case 3 that is adjacent to the clips 6 to receive the pins 7. The opening 2 is somewhat wider than the width of the case 3, and the 45 clips 6 force said case against the opposite side of said opening and hold it there normally. There is sufficient clearance to enable the case to be inserted in and removed from the plate 1.

50 Secured to the back side of the plate 1, between the clips 6, is a keeper 9 in which is a horizontal sliding bolt 10 adapted at its inner end to enter an opening 11 in the adjacent side of the case 3. The bolt 10 is actuated 55 toward the case 3 by means of a spring 12 which is received in a longitudinal slot 13 in said bolt, between the inner end of said slot and a lip 14 extending forwardly into 60 said slot from the outer end of the back side of the keeper 9. The bolt 10 at the outer end is provided with a lug 15 to limit the movement imparted to said bolt by the spring 12.

On the front side of the plate 1 is a rotary 65 knob 16, and on the front side of the case 3

near the top thereof is a vertically-movable knob 17, below that a horizontally-movable knob 18 and a plate 19 which covers a slot 20 in said front side of the case, below said last-named knob and plate are 70 three push-pins 21, and below the center push-pin is a push-pin 22.

Secured to the back side of the plate 1, on the side of the case 3 that is opposite to that where the keeper 9 is located, is a plate 23 75 having in the outer portion thereof a slot 24 that is parallel with the longitudinal center of the plate 1, and an arcuate slot 25 into the inner or lower end of which said first-named slot opens. In the outer end of the 80 slot 24 is a rearwardly extending lug or stop 26. A slide 27 is located on the back side of the plate 23, and held in position against said plate, by a bracket 28 that is secured to the plate below said slide and extends forwardly and upwardly behind the same. The bottom, longitudinal edge of the slide 27 is supported on the bracket 28, and said slide at the inner end is pivotally connected at 29 with an extension 30 from the 85 outer end of a horizontal, main, lock bolt 31. At the outer terminal the slide 27 projects rearwardly and then outwardly to form a lip 32, and on the back side of said lip is secured a block 33 of insulating material. 90 A spring 34 has one terminal secured to a screw 92 and a pin 93 set in the plate 23, and the other terminal of said spring bears against the upper edge of the slide 27 and normally retains said slide in horizontal 95 position. Extending rearwardly from the upper edge of the lip 32 is a lug or stop 35 adapted to operate in the slots 24 and 25. When the stop 35 is in the slot 24, said stop is in line with the stop 26, but inwardly disposed relative thereto. The spring 34 bearing against the slide 27 normally retains the same with the stop 35 against that part of the plate 23 which forms the bottom edge of the slot 24 and the bottom end of the 100 slot 25, which edge and end are in the same horizontal plane. Secured to the back side of the insulating block 33 is a contact member 36 having rearwardly and inwardly extending arms with upper and lower, semi-spherical contact-points 37 and 38, respectively, at their ends.

The knob 16 is mounted on the forward end of a spindle 39, which spindle is journaled in the plates 1 and 23, and has rigidly secured thereto behind said last-named plate an arm 40. The arm 40 has therein a longitudinal slot 41 to receive a pin 42 that extends forwardly from the lip 32 adjacent to the outer edge thereof.

Mounted on and secured to the back side of the plate 1, by means of two upper, foot-provided legs 94, and a lower, foot-provided leg 95, is a plate 43 of insulating material—see Figs. 2 and 3. The insulating plate 130

43 extends over the lip 32 behind the contact-points 37 and 38, and is provided with three binding-posts 44, 45, and 46 respectively, one below the other in the order named. Each of these binding-posts is set into a contact-point let into the front or inner side of the insulating plate 43, one of said contact points being shown at 96 in Fig. 2. The contact-points (96) for the three binding-posts are in position to have engaged therewith and disengaged therefrom the contact-points 37 and 38, in the manner hereinafter described. The exposed ends of the binding-post contact-points are concave or recessed to receive the contact-points 37 and 38 and thereby insure good connections. The concavo-convex formation of the contact-points (37-38 and 96) also causes the connections to be maintained when the slide 27 is moved out of its normal horizontal position, as presently explained. A wire 47 extends from the binding-posts 44 to the battery (not shown), a wire 48 extends from the binding-post 45 to the coil (not shown), and a wire 49 extends from the binding post 46 to the magneto (not shown). In the event no magneto be present, the binding-post 46 and the wire 49 are omitted.

When the slide 27 is in its retracted position, with the stop 35 in the lower end of the slot 25, the contact-points 37 and 38 are in engagement with the ends of the contact-points of the binding-posts 45 and 46, respectively, and the circuit is closed between the coil and the magneto, through the wires 48 and 49, and said binding-posts and contact-points. Upon turning the knob 16 in the direction to swing the slide 27 on the pivot 29 upwardly, through the medium of the arm 40 and the pin 42, the stop 35 then traveling upwardly in the slot 25 to the upper end thereof, which end limits the movement of the parts in this direction, the contact-points 37 and 38 are moved into engagement with the contact-points of the binding-posts 44 and 45 respectively, and the circuit is closed between the coil and the battery. The resiliency of the arms of the contact member 36 is sufficient to produce the necessary frictional resistance between the contact-points to retain them in engagement with each other against the force of the spring 34, until such time as the knob 16 is partially rotated in the opposite direction to swing the slide 27 downwardly again into the normal horizontal position. The return of the slide to the aforesaid position carries the contact-points 37 and 38 into engagement again with the contact-points of the binding-posts 45 and 46, respectively.

When the slide 27 is in advanced position, it is there held against upward movement by the stop 35 which is then in the slot 24. The stop 26 prevents the slide 27 from being advanced, when thrown up in position

to connect the battery with the coil, in the event the main bolt be released, and thus breaking the contact. In that case the outer edge of the lip 32 immediately encounters the inner end of the stop 26 and the outward movement of the slide 27 is arrested, but said slide can nevertheless be swung down by means of the knob 16 when said slide immediately moves into its most advanced position.

A cover 50 has the longitudinal edge thereof that is adjacent to the keeper 9 hinged, by means of a rod 51, to the corresponding side of the case 3. The rod 51 passes through openings in the top and bottom sides of the case 3, and through a sleeved part of the aforesaid longitudinal edge of the cover 50. In the edge portion of the cover 50, which is opposite to that where said cover is hinged to the case 3, is an opening 52, and the case 3 is provided at 53 with a spring latch to enter said opening, when said cover is closed, and retain the same in closed position. Formed in the cover 50 are three vertical channels 54 shaped to receive and permit to slide therein a corresponding number of lock-bars 55.

Each lock-bar 55 is T-shaped in cross section, provided on the front side with a plurality of ratchet teeth 56, and has therein above said ratchet teeth a notch 57. The notches 57 in the lock-bars 55 are disposed at different distances from the upper ends thereof, but said lock-bars themselves are all the same length. At the bottom of each lock-bar is a rearwardly extending lip 58, and there is a forwardly extending lip 59 at the top of each channel 54. A spring 60 is located in each channel 55 between the lips 58 and 59 and behind the lock-bar therein. The springs 60, therefore, have a constant tendency to force the lock-bars downwardly. The lock-bars 55 are prevented from dropping out of the bottoms of the channels 54, when the cover 50 is open, by a spring 61 that is coiled around the rod 51 just above the bottom side of the case 3, and has a projection 62 that extends into said case. The lips 58 on the lock-bars are a little above the bottom ends thereof, and the spring 61 is introduced behind said lock-bars at points below said lips. On the back side the cover 50 is provided, at the bottom and adjacent to the free longitudinal edge of said cover, with a vertical, resilient finger 63 that has a pin 64. The finger 63 is fastened at the upper terminal to the cover and extends downwardly a short distance below the bottom edge of said cover, and the pin 64 extends forwardly from said finger through an opening in the adjacent corner of the cover. The spring 61, when in supporting position relative to the lock-bars 55, is held in place from below by the pin 64 which then engages the outer terminal por-

tion of said spring. When it is desired to release the lock-bars 55, as for the purpose of changing the combination, the finger 53 is forced rearwardly at the bottom to withdraw the pin 64 from beneath the spring 61, and said spring is moved out of engagement with said lock-bars and swung out of the way to permit to be made whatever changes may be required, after which said spring is returned to place beneath the lock-bars and secured with said pin. The lock-bars, when unconfining by the spring 61, can be slipped out of the lower ends of the channels 54 and transposed or rearranged, and then slipped back into said channel, or new lock-bars may be substituted for the old ones. When the lock-bars are all supported on the spring 61, the notches 57 are out of line with each other.

Extending transversely across inside and secured to the front of the case 3 is a plate 65, and the main bolt 31 is slidingly arranged on the back side of said plate. In and opening through the inner end of the bolt 31 is a longitudinal slot 66, and extending through said slot to be tapped into the plate 65 is a screw 67. There is an opening 68 in the side of the case 3 which is adjacent to the switch members, through which opening the outer-terminal portion of the bolt 31 extends. The bolt 31 is slidingly held in place against the plate 65 by the screw 67 and some portion of said bolt which is always in the opening 68.

The slot 20 not only extends through the front side of the case 3, but also through the plate 65. The knob 18 and the plate 19 are secured to a stud 69. The stud 69 passes through the slot 20, and has its rear end secured to the bolt 31. It follows, therefore, that the bolt 31 can be moved longitudinal from outside of the case 3 by means of the knob 18. Extending rearwardly from the upper edge of the bolt 31, within the case 3, is a flange 70 notched or cut away in three places, as represented at 71, to provide recesses for the lock-bars 55 when in operative position. A notch 72 is provided in the upper part of the bolt 31 to receive the lower end of a vertical latch 73, when said bolt is retracted and said notch locked below said latch. A stud 74 projects into the case 3 from the front side thereof, and a spring 75 is arranged on said stud to bear on the inner end of the flange 70 to force it with the bolt 31 outwardly, when said bolt is released to said spring, and yieldingly hold said bolt in such position. The flange 70 at the outer end and a shoulder on the bolt 31 below respectively encounter the upper and lower edge portions of the slot 68 and limit the outward movement of the bolt.

The latch 73 is arranged to slide vertically in a pair of lugs 76 on the back side of the plate 65. The knob 17 is mounted on a stud 77 which extends through a vertical slot 78 in the front of the case 3, and through and beyond the latch 73. The slot 78 permits the stud 77 to move up and down to the extent necessary to position the latch 73 in and out of locking engagement with the bolt below. A second spring 78 is attached to the stud 74 and arranged to bear on the top of the stud 77, and thereby either to retain the bottom of the latch 73 on the top of the bolt 31, or to force said latch into the notch 72 when the same is located directly below the latch. When the bolt 31 is retracted, against the resiliency of the spring 75, said bolt is held in retracting position by the latch 73, but by raising said latch, against the resiliency of the spring 78, out of engagement with said bolt, the latter is advanced by said first-named spring, until the flange 70 encounters the side of the case in which is the slot 68.

Each of the three push-pins 21 is provided with a lifter 79 for engagement with the teeth 56 of the adjacent lock-bar 55. This lifter consists of a piece of wire having its terminals secured in the plate 65 and extending below said plate as two parallel arms 80, then being formed into a coil 81 at the bottom of said arms, and finally being carried upwardly and rearwardly to form the direct lifting element which is in the form of a triangle having its base uppermost, as best shown in Figs. 9 and 10. The inner end of the push-pin 21 has ears which are extended inwardly to produce an eye for the coil 81, said ears being bent over into said coil after it has been formed. The push-pins 21 are loosely arranged in openings in the front side of the case 3, and are normally held, by the arms 80 of the lifters 79 with which said push-pins are connected, in their advanced position, said lifters then being out of contact with the lock-bar teeth 56. Upon forcing any push-pin 21 inwardly, against the resiliency of the arms 80 of the connected lifter 79, said arms are bent rearwardly, and said lifter is carried rearwardly and upwardly, with the result that the lock-bar 55 behind is raised the distance of one tooth 56. Then, upon the release of the push-pin, the spring arms 80 cause the lifter 79 to be moved forward and the push-pin to be actuated into its outward position.

Each time any lock-bar 55 is elevated, against the resiliency of its spring 60, by the associated lifter 79, said lock-bar must be held against downward movement, and to this end I provide in the lower part of the case 3 and in front of the three lock-bars a detent 82 which has side arms pivotally connected at 83—83 with opposite sides of said case, and also has three fingers 84 that at the top incline upwardly and rearwardly to engage the teeth 56 of said lock-bars. The cen-

tral portions of the fingers 84 are cut out to accommodate the actuating parts of the lifters 79. When the cover 50 is closed, the spring extension 62 bears against the bottom part of the detent 82 and forces it against the front side of the case, thus causing the fingers 84 to engage the lock-bar teeth 56. The inner end of the push-pin 22 is secured to the detent 82 in the vertical center near the bottom thereof. Upon forcing the push-pin 22 inwardly, the detent 82 is rocked on its pivots 83, against the resiliency of the spring extension 62, and the fingers 84 are withdrawn from engagement with the teeth 56, so that any and all of the lock-bars 55 which have been elevated are permitted to descend, under the influence of the springs 60, into their low position on the spring 61. The detent 82 thus serves the double purpose of holding any lock-bar 55 against downward displacement each time it is stepped up by the associated lifter 79, and of releasing any or all of the lock-bars and permitting them to descend into initial position.

25 The extension 62, of the spring 61, serves further as means for causing the cover 50 to fly open when released from the latch 53.

In the present example, the notches 57 in the outer lock-bars 55 are in line with each other and in position to receive therein the bolt flange 70, but the notch 57 in the middle lock-bar 55 must be elevated from its low position in order to locate said last-named notch in position to receive said flange.

30 The cover 50 can be closed only when the bolt 31 is in advanced position, since then all of the lock-bars 55 can enter the recesses 71 provided for them in said flange.

Ordinarily there will be more than three lock-bars 55, and a correspondingly greater number of recesses 71, lifters 79 and push-pins 21, detent fingers 84, and other parts and members closely associated with those just mentioned. The greater the number of lock-bars the more difficult the combination, of course, and the less liability of an unauthorized person being able to work out the combination.

The main bolt 31 is in line with the bolt 10, and adapted when retracted to force said last-named bolt outwardly, against the resiliency of the spring 12, until it is clear of the case 3.

That part of the bolt 31 from which the extension 30 projects may be thicker than the main portion of said bolt and is indicated by the numeral 85.

When the parts and members are disposed as illustrated in Figs. 1, 3, 5, and 8, the bolts 31 and 10 are in locking position, and the case 3 cannot be removed from the plate 1, because of the engagement of said first-named bolt with said plate behind the same, and the engagement of said second-named bolt with said case, and the movable switch

members are entirely out of contact with the fixed switch members, and locked in such position, the final locking element or elements being one or more of the lock-bars 55 in one or more of the recesses 71 in the bolt flange 70, whereby said flange with its bolt is prevented from being actuated inwardly or retracting. Here only the middle lock-bar 55 is in locking engagement with the flange 70, being in the central recess 71. Starting with the parts and members disposed as and in the manner just explained, the complete separation of the lock is described as follows:

To release the bolt 31 from the lock-bars 55, it is necessary to set the combination with the push-pins 21. In the present example it is necessary only to impart one pulsation to the middle lock-bar 55, by means of the associated lifter 79 and the attached push-pin 21. The middle push-pin is forced inwardly and carries with it rearwardly and upwardly the attached lifter 79, the arms 80 above the coil 81 of said lifter being at this time sprung rearwardly away from the front of the case. The movement thus imparted to the middle lifter causes the same to engage the middle lock-bar 55 and raise it one tooth, the tooth 56 that is in engagement with the intermediate detent finger 84 passing upwardly from said finger, and the latter taking position in supporting relation to the next tooth 56 below, so that, when the lifter swings forwardly, upon the release of its push-pin 21, out of engagement with the lock-bar said lock-bar is prevented from descending. This movement upward of the intermediate lock-bar locates the notch 57 therein in the same horizontal plane with the notches 57 in the other two lock-bars, and all of said notches are now in the same horizontal plane with the bolt flange 70.

100 The push-pins 21 are loosely arranged in the front of the case and thus enable the lifters 79 to be effectively operated thereby.

Obviously, the notch 57 might be so located in the middle lock-bar 55 that two, three, or more pulsations would have to be imparted to the associated push-pin 21 in order to raise said lock-bar far enough to locate said notch in the same horizontal plane with the bolt flange 70; and the notch 57 in each of the other lock-bars might be so located therein as to require that said last-named lock-bar be elevated, by imparting thereto one or more pulsations, before it would be located in unlocking or releasing position. Furthermore, it should be observed at this point that, if either of the outer push-pins 21 be operated, the lock-bar 55 controlled thereby, and with the notch 57 located therein as here shown, is elevated, with the result that said notch is raised above the plane of the bolt flange 70, a solid part of said lock-bar is positioned in

the adjacent recess 71, and the bolt 31 is thereby held against inward movement. Due to the fact that one or more of the lock-bars 55 may have been so disposed relative to the flange 70 as to prevent the bolt 31 from being retracted after the combination has been worked, it is generally necessary, before proceeding to work the combination, to force the push-pin 22 inwardly and so rock the bottom part of the detent 82 in the same direction, on the pivots 83 and against the resiliency of the spring extension 62, thus withdrawing the fingers 84 from engagement with the teeth 56 on all of the lock-bars 55, and enabling the springs 60 to actuate downwardly said lock-bars or any of them which may be in elevated position.

Having worked and set the combination, the operator moves the knob 69 to the left, and thereby actuates the bolt 31 inwardly until the latch 73 moves into engagement therewith. In moving inwardly the bolt 31 forces the bolt 10 out of engagement with the case 3, and draws inwardly the slide 27 until the contact-points 37 and 38 are in engagement with the contact-points 96 of the binding-posts 45 and 46, respectively. The stop 35 is now located in the bottom of the slot 25. When the slide 27 is in this position it can be swung upwardly on its pivot 29, by means of the knob 16, into the position illustrated in Fig. 6, to engage the contact-points 37 and 38 with the contact-points 96 of the binding-posts 44 and 45, respectively.

While the parts and members are disposed in the manner last explained, but with the slide 27 down in its horizontal position, the case 3 can be removed from the plate 1, after taking out the screws 4, simply by forcing the side of said case with which the clips 6 are in contact out of the opening 2, and then taking the case bodily from the plate. The clips 6 yield sufficiently at this time to enable the case to be withdrawn from engagement with the pins 7, and the pivot 28, being attached to the extension 30, is tilted and lifted out of engagement with the slide 27, the opening in said slide for said pin being sufficiently large for the purpose.

While the case 3 is out of the plate 1, said case can be opened by forcing the exposed end of the latch 53 outwardly to release the cover 50 to the spring extension 62. Access is thus had to the interior of the case, and to the lock-bars 55, and the latter, after releasing them from the spring 61 can be rearranged or exchanged for others. After changing the combination and replacing the spring 61 in supporting position beneath the lock-bars 55, the cover 50 is closed, against the resiliency of the spring extension 62, engaged by the latch 53, and the case 3 is inserted again in the opening 2, the

side of said case from which the extension 30 projects being introduced first, and then the opposite side being forced inwardly until the pins 7 again engage the recessed parts 7' of the contiguous side of the case, the pivot pin 29 meanwhile being caused to reassume its engagement with the slide 27. Upon the removal of the case 3 from the plate 1, the spring 12 actuates the bolt 10 inwardly until the lug 15 contacts with the keeper 9, and the inner end of said bolt extends over the opening 2, but upon the insertion of the case 3 in the opening 2 the case encounters said inner end and forces said bolt out of the way, although the bolt finally enters the slot 11 in said case.

To lock the parts, the latch 73 is raised, by means of the knob 77, to withdraw the lower end of said latch from the recess 72 in the bolt 31, when said bolt is shot by its spring 75. In moving outwardly, the bolt 31 carries the contact-points 37 and 38 beyond the contact-points 96 of the binding-posts 45 and 46, and thus breaks the circuit through the switch—see more especially Figs. 3 and 4. In the event the bolt 31 be released while the slide 27 is in the position shown in Fig. 6, the outer edge of the lip 32 encounters the stop 26 and holds the parts until said slide is actuated downwardly by means of the knob 16 as far as permitted by the stop 35. As soon as the stop 35 is in line with the slot 24, the spring 75 forces the bolt 31 outwardly and with it the slide 27. Upon the advance of the bolt 31 the bolt 10 under the influence of the spring 12 moves into locking engagement with the case 3. Finally the push-pin 22 should be actuated to bring about the release of the intermediate lock-bar 55 from the intermediate, engaging detent finger 84, and thus permit said lock-bar to descend and locate a solid part of the same in the intermediate recess 71 in the flange 70, thereby locking the bolt 31 against inward movement. Until and unless the detent 82 be operated by the push-pin 22, after the bolt 31 has been released by the latch 73, said bolt can be retracted at any time by means of the knob 18 and reengaged by said latch.

Although it is necessary to advance the bolt 31 in order to enable the cover 50 to be closed, said bolt must be retracted before the case is inserted in the plate 1.

If the lock is to be applied to drawers, doors, and the like, the extension 30 is omitted from the outer end of the bolt 31. When the lock is to be applied to dress-suit cases and the like, I provide the bolt at the outer terminal with a tumbler 87 which is pivotally connected at 88 with said bolt, and has a lock-hook 89 and a finger 90. In this example the thick, outer-end portion of the bolt 31 is recessed to receive the tumbler 87, and said tumbler is so pivotally con-

nected therewith that either the lock-hook 87 or the finger 90 may project beyond one longitudinal edge of said portion.

As will be seen from Figs. 11 and 12, when the bolt is advanced the tumbler 87 is carried outwardly, through the slot 68 in the adjacent side of the case 3, into and through a slot 91 in a lock-plate or keeper 86, and, as said tumbler passes through said slots, 10 the finger 90 encounters the side of the case below the slot 68 and causes the tumbler to make a partial revolution on the pivot 88 until, by the time said bolt has reached the end of its travel, the lock-hook 89 is moved 15 into engagement with said keeper at a point inside of said slot therein. The part of the case 3 below the slot 68 and the part of the keeper 86 below the slot 91 are now in the notch or indentation between the lock-hook 20 89 and the finger 90, so that any force applied to separate said case and keeper, acting through said lock-hook, causes said finger to bear against the case and thus prevent such separation to take place—see Fig. 11. 25 Upon the retraction of the bolt 31, the lock-hook 85 slides over the bottom edge of the slot 91, causes the tumbler 87 partially to rotate, and finally slides over the bottom edge of the slot 68 into the position shown 30 in Fig. 12, said finger then meeting with no obstruction and moving into a downward position.

More or less change may be made in the shape, size, construction, and arrangement 35 of some or all of the parts of this combination lock, in addition to the changes hereinbefore specifically pointed out, without departing from the spirit of my invention or exceeding the scope of what is claimed.

40 What I claim as my invention, and desire to secure by Letters Patent, is—

1. In a combination lock, a plate having an opening therein, a case receivable in said opening, and yielding means normally to retain 45 said case in place therein.

2. In a combination lock, a plate having an opening therein, and provided with spring clips adjacent to one edge of said opening, and a case receivable in said opening and adapted when therein to be engaged by said clips.

3. In a combination lock, a case, a channeled cover for said case, spring-pressed lock-bars in the channels in said cover, and 55 releasable means to prevent said lock-bars from escaping from said channels.

4. In a combination lock, a case, a channeled cover for said case, spring-pressed lock-bars in the channels in said cover, and 60 a spring adapted to be located in position to prevent said lock-bars from escaping from said channels, said spring being releasable from such position.

5. In a combination lock, a case, a channeled cover for said case, said cover being

provided with a latch, spring-pressed lock-bars in the channels in said cover, and a pivotally mounted member adapted to be located in position to prevent said lock-bars from escaping from said channels, and when 70 in such position to be engaged by said latch.

6. In a combination lock, a case provided with a latch, a channeled cover hinged to said case, spring-pressed lock-bars in the channels in said cover, a spring pivotally 75 connected with said case, adapted to be located in position to prevent said lock-bars from escaping from said channels, and having an extension which bears against said case and is adapted to open said cover when 80 the same is released from said latch.

7. In a combination lock, a case, a lock-bar detent pivotally mounted on said case, a channeled cover for said case, spring-pressed lock-bars in the channels in said 85 cover, and a spring pivotally connected with said case and adapted to be located in position to prevent said lock-bars from escaping from said channels, and having an extension bearing on said detent normally to 90 retain the same in engagement with said lock-bars.

8. In a combination lock, a case provided with a latch, a channeled cover hinged to said case, spring-pressed lock-bars in the channels in said cover, a detent for said lock-bars, said detent being pivotally mounted in said case, and a spring pivotally connected with said case, adapted to be located 100 in position to prevent said lock-bars from escaping from said channels, and having an extension adapted normally to retain said detent in engagement with said lock-bars, and to open said cover when released from 105 said latch.

9. In a combination lock, a case, a cover for said case having channels therein and provided with lips, lock-bars provided with lips, said lock-bars being in said channels, 110 and springs in said channels between said cover lips and said lock-bar lips.

10. The combination, in a lock of the class described, with a case, a cover for said case, serrated lock-bars slidably arranged in said cover, and a detent in said case for said lock-bars, of push-pins in the front of said case, and resilient lifters for said lock-bars, said lifters being affixed to said case, and operatively connected with said push-pins.

11. The combination, in a lock of the class described, with a case, a cover for said case, and serrated lock-bars slidably arranged in said cover, of lifters for said lock-bars, each of said lifters comprising a spring having its ends secured to said case, extended in the form of approximately parallel arms from the points of attachment, and then coiled and looped to form a part to engage one of said lock-bars, a push-pin slidably arranged in the front of said case, and hav- 125 130

ing an eye with which said coil is in engagement, and a detent for said lock-bars.

12. The combination, in a lock of the class described, with a case, a cover for said case, and serrated lock-bars slidably arranged on said cover, of means in said case to impart a step-by-step movement to said lock-bars, a spring-pressed detent pivotally mounted in said case and having fingers to engage said lock-bars, and a push-pin slidably arranged in the front of said case, and attached to said detent, whereby the latter is actuated to disengage said fingers from said lock-bars.
13. The combination, in a lock of the class described, with a plate having an opening therein, and a spring-pressed bolt mounted on said plate adjacent to said opening and adapted when released to its spring to engage said case, of a case receivable in said opening, a main bolt slidably arranged in said case, and adapted when in advanced

position to engage the inside of said plate, said first-named bolt being in the path of said main bolt when the latter is retracted, 25 permutation means to lock said main bolt in advanced position, and exterior means to retract said main bolt when released by said permutation means.

14. In a combination lock, a lock-bar having therein a notch, and provided with teeth to be engaged by a detent and a lifter.

15. In a combination lock, a lock-bar having therein a notch, and provided with teeth to be engaged by a detent and a lifter, and 35 with a spring-supporting lip.

16. In a combination lock, a lock-bar having therein a notch, cut away at the bottom to receive a supporting member, and provided with teeth to be engaged by a detent 40 and a lifter, and with a spring-supporting lip.

DARIO ROBERTI.
